UNITED STATES PATENT OFFICE.

BROR KNUT LINDBERG AND ALBIN FREDRICK HÖRLIN, OF STOCKHOLM, SWEDEN.

FLOOR-COVERING.

1,257,503.

Specification of Letters Patent. Patented Feb. 26, 1918.

Application filed May 16, 1917. Serial No. 169,086.

To all whom it may concern:

Be it known that we, BROR KNUT LINDBERG and ALBIN FREDRICK HÖRLIN, subjects of the King of Sweden, residing at Grefturegatan 13 A, Stockholm, Sweden, and Grefturegatan 13, Stockholm, Sweden, have invented new and useful Improvements in Floor-Coverings, of which the following is a specification.

10 This invention relates to flexible floor-coverings and in particular to floor-coverings comprising strips or pieces of wood secured to and supported by a backing of fabric. It has been found that floor-coverings of this kind are not always satisfactory as regards wear and durability as it is very difficult to attach the rigid strips of wood to the flexible fabric in a thoroughly secure and reliable manner. It is the object of the 20 present invention to overcome this difficulty and, to this end, the invention consists in interposing between the rigid strips of wood and the fabric backing a layer of veneer, which, as regards strength and flexibility, 25 has properties intermediate between those of the wooden strips and the fabric, so that such layer is well adapted to be combined with and secured to both the rigid strips of wood and the fabric, thus affording a permanent, strong and flexible connection between the two.

The accompanying drawing illustrates by way of example a floor-covering embodying the present invention in which strips or 35 pieces of wood 1 are secured to a layer of veneer 8 by means of glue or other suitable adhesive means while a textile fabric 9 is secured to the opposite side of the veneer in a similar way. The back of the fabric 40 may be impregnated with oil or other suitable waterproofing material such as paint, pitch, resin, tar and the like or, alternatively, it may be covered with oiled or otherwise impregnated paper or fabric for pre-

venting moisture from penetrating the support and coming into contact with the glue or other adhesive means when the floor-covering is in use. 45

For convenience the floor-covering according to the invention is manufactured in longitudinal strips which may be arranged side by side when the width of the floor is greater than that of the floor-covering. In order to increase the strength and improve the appearance of the joints between adjacent longitudinal strips the wood covering of one strip is preferably arranged to overlap the fabric and veneer backing of the adjacent strip to which it may be secured by means of glue or other suitable adhesive 55 means. 60

It will be understood that the invention is not limited to the exact embodiment shown although the use of a backing of veneer in flexible floor-coverings is not claimed broadly herein, the same being well known in the art. As stated above it has been found, however, that distinct and important advantages are obtained by the novel arrangement set forth in the appended claim. 70

We claim:

A floor covering comprising a series of strips of wood, a flexible fabric backing for said strips, and a sheet of veneer interposed between and secured to said strips and fabric backing, said sheet of veneer having a flexibility intermediate between that of the strips of wood and that of the fabric backing. 75

In testimony whereof we have signed our names to this specification in the presence of two subscribing witnesses.

BROR KNUT LINDBERG.

ALBIN FREDRICK HÖRLIN.

Witnesses:

HARRY HAMMAR,
JACOB BAGGE.
